Primary Examiner — Shannon W Morgan*Assistant Examiner* — Aula Soroush(74) *Attorney, Agent, or Firm* — COOLEY LLP(57) **CLAIM**

The ornamental design for a nozzle for an ear cleaning device, as shown and described.

DESCRIPTION

FIG. 1 is a front perspective view of a nozzle for an ear cleaning device;

FIG. 2 is a back perspective view of the nozzle illustrated in FIG. 1;

FIG. 3 is a front view of the nozzle illustrated in FIG. 1;

FIG. 4 is a back view of the nozzle illustrated in FIG. 1;

FIG. 5 is a right side view of the nozzle illustrated in FIG. 1;

FIG. 6 is a left side view of the nozzle illustrated in FIG. 1;

FIG. 7 is a top view of the nozzle illustrated in FIG. 1; and,

FIG. 8 is a bottom view of the nozzle illustrated in FIG. 1.

The broken lines in the drawings illustrating portions of the nozzle for ear cleaning device and form no part of the claimed design. The dot-dash broken lines illustrate the boundary of the nozzle for ear cleaning device and form no part of the claimed design. The wavy dot-dash broken lines illustrate a break in length in the nozzle for ear cleaning device that forms no part of the claimed design.

1 Claim, 8 Drawing Sheets(56)
